Patented Mar. 5, 1918.

FIG. 1.

FIG. 5.

UNITED STATES PATENT OFFICE.

ALFRED HUTCHINSON, OF CLEVELAND, OHIO.

NECKTIE-SUPPORTING DEVICE.

1,258,572.

Specification of Letters Patent.

Patented Mar. 5, 1918.

Application filed January 30, 1917. Serial No. 145,388.

To all whom it may concern:

Be it known that I, ALFRED HUTCHINSON, a subject of Great Britain, residing at Cleveland, in the county of Cuyahoga and State of Ohio, have invented a certain new and useful Improvement in Necktie-Supporting Devices, of which the following is a full, clear, and exact description, reference being had to the accompanying drawings.

The object of this invention is to provide an effective removable necktie support about which a tie or scarf of ribbon form may be wound into a "knot", which may then be easily mounted on a collar stud and retained in place by the stud and the wings of the collar. In accomplishing this I have provided a very simple, cheap and light supporting device which has wings adapted to lie behind the collar flaps, a downwardly extending portion to support the tie loop or knot, and a suitable retaining device to engage the collar stud. My support may be so shaped as to hold the tie with the crossing portion or knot having the desired convex form, both horizontally and vertically, giving it the attractive appearance of a "four-in-hand".

One of the advantages of my device is that it enables a tie to be put in place on a collar while the latter is buttoned onto the wearer's shirt. Accordingly, it is unnecessary to remove the collar to change the tie. Another advantage is that it enables the use of the ordinary comparatively cheap ribbon scarf for a bow-tie after the manner of a four-in-hand. A much shorter tie may thus be used with the consequent saving in cost.

My device not only is readily attachable to the collar, and avoids the necessity of passing the tie completely around the collar, as above stated, but the device also serves to keep the scarf in good condition, so that it is not subjected to the wear usually incident to being tied in a hard knot or drawn back and forth across the collar stud.

My device is illustrated in the drawings hereof, and is hereinafter more fully described and claimed. In these drawings, Figure 1 is a front elevation of a collar with the tie and the supporting device in place; Fig. 2 is a similar view on a larger scale of the support and tie removed; Fig. 3 is a front elevation of the support; Fig. 4

is a vertical central section of the support in place; Fig. 5 is a cross section substantially on the line 5—5 of Fig. 3; Fig. 6 is a view of the clip which secures the device to the collar stud.

The body of my supporting device, as shown in the drawings, consists of a substantially flat arc-shaped plate A, providing the desired lateral wings for engaging the collar flaps, and a downwardly extending outwardly bowed central tongue B, secured to the plate A, and adapted to support the tie knot. These parts may readily be made of metal, celluloid, or other suitable material. As shown the part B is secured to the part A by eyelet rivets C.

The tongue portion B is outwardly bowed centrally, as illustrated at b in Fig. 4, while transversely this part is constricted to give it a substantial V-shape at its center, as appears in Fig. 5, and at b' in Fig. 3. This peculiar shape is adapted to cause the tie, where it crosses the tongue horizontally and vertically, to have substantially the appearance of a four-in-hand knot.

D, in Figs. 2, 3, 4 and 6, indicates a clip adapted to fasten the device to the front collar stud. This consists of a suitable plate having a key-hole opening d therein. The fastening clip D is secured to the vertical tongue B by means of an elastic cord E.

It is very convenient to loop the elastic cord E in the following manner: It is doubled on itself and looped through two openings d' of the fastening clip; then the two reaches e of the cord pass to the under side of the tongue B and through openings b³ therein, out to the front, as shown at e'; thence through a central opening b⁴ in the tongue and upwardly side by side on the rear side of the tongue, being secured to the tongue near the upper end. To effectively anchor the elastic cord to the tongue B, and at the same time allow ready removal for the substitution of a new cord, I prefer to provide a key-hole opening in the upper portion of the tongue, through which a knot at the end of the elastic cord may be passed and caught. As shown two reaches 105 of the cord come forwardly through an opening b⁵ in the tongue, and then pass rearwardly into a key-hole opening b⁶. The knot e² at the upper end of the cord is readily passed through this opening, but is 110 caught behind the reduced lower extension or key-hole portion of the opening. The

above arrangement is a convenient, though not a necessary way, of elastically securing the clip to the tongue piece.

It will be seen that my supporting device is extremely simple in construction and operation, consisting primarily of the main support, the attaching clip, and the elastic connection between the two.

In placing the tie on the support it is very convenient to hold the support facing forwardly in the left hand; then to double the tie into a single loop and hang it over the top of the arc-shaped piece with one length of it, T', Fig. 2, hanging down on the front 10 of the arc-shaped piece; then the rear portion is brought from beneath the arc-shaped piece around over the front portion and over the tongue piece horizontally as at T'', and then passed upwardly behind the arcual 15 member and then pulled down through the transverse or knot portion thus provided, producing the front flap T''. The operation described brings the scarf into the form shown in Figs. 1 and 2, which corresponds in 20 25 appearance to a tied four-in-hand scarf.

The above described method of tying the scarf is only one of several ways of mounting the tie on the support. Some find it more convenient to loop the tie first about 30 their fingers and then pass the support into place through the tie loops thus provided, then withdrawing the fingers and pulling the tie with sufficient tightness about the support, or two portions of the tie may be

looped or twisted to produce two bights, 35 which are then passed over the wings and the tie drawn to proper tightness.

When the tie has been placed on the support to mount the tie in position within the collar flaps, it is only necessary to hook the 40 fastening clip onto the collar stud and pass the wings upwardly behind the flaps of the collar, or, if desired, bend them toward each other and spring them behind the flaps.

Having thus described my invention, what 45 I claim is:

In a device of the character described, the combination of a supporting member for the knot of the tie, said member being made of thin material and bowed outwardly on 50 the front side to provide a recess at the rear of the member, a thin arc-shaped plate to the midde of which said member is riveted at its upper end, a plate provided with an opening adapted to hook over the collar 55 stud, and an elastic cord having a knot at its upper end which occupies and is held by a key-hole slot in the supporting member, said cord passing downwardly on the front side of the supporting member and then through 60 a hole to the rear side of the supporting member and then downwardly on the rear side thereof and guided adjacent to the lower end of the support and connected with the plate provided to engage the collar stud. 65

In testimony whereof, I hereunto affix my signature.

ALFRED HUTCHINSON.
